UNITED STATES PATENT OFFICE.

WILLIAM L. CASADAY, OF SOUTH BEND, INDIANA.

MALLEABLEIZING AND ANNEALING OVEN.

No. 798,723.

Specification of Letters Patent.

Patented Sept. 5, 1905.

Application filed June 20, 1904. Serial No. 213,239.

To all whom it may concern:

Be it known that I, WILLIAM L. CASADAY, a citizen of the United States, and a resident of the city of South Bend, county of St. Joseph, 5 and State of Indiana, have invented certain new and useful Improvements in Malleableizing and Annealing Ovens; and I do hereby declare that the following is a full, clear, and exact description of the same, reference being 10 had to the accompanying drawings, and to the letters of reference marked thereon, which form a part of this specification.

This invention relates to improvements in malleableizing and annealing ovens of that 15 class adapted to receive the material to be treated therein, dispensing with the use of saggers, pots, or other receptacles of any kind other than the oven itself.

The object of the invention is to provide a 20 construction adapted to facilitate the malleableizing or annealing of castings by packing the same, either with or without a cementing material, into the oven and conveying the heat around the oven and through all parts of the 25 material, thus forming greater uniformity of the temperature for the mass as a whole and facilitating the operation, as well as providing a more perfect and uniform treatment of the casting.

30 The invention embraces many novel features; and it consists in the matters herein-after described, and more fully pointed out and defined in the appended claims.

In the drawings, Figure 1 is a fragmentary 35 perspective view of a malleableizing or annealing oven embodying my invention. Fig. 2 is a section taken on line 2 2 of Fig. 6. Fig. 3 is a section taken on line 3 3 of Fig. 2. Fig. 4 is a section taken on line 4 4 of Fig. 5. Fig. 40 5 is a central transverse section. Fig. 6 is a section taken on line 6 6 of Fig. 5. Fig. 7 is a section taken on line 7 7 of Fig. 5.

As shown in said drawings, said oven is 45 constructed with the floor *x* thereof at or below the surface *X* of the ground and is provided with a central longitudinal furnace-chamber extending therethrough below the floor, having a continuous grate *A* therein extending from end to end of the oven, below 50 which is the usual ash-pit and above which is the fire-box. Said oven comprises side walls *B* *B'* and a rear and front end wall *B*² and *B*³ and an arched roof *B*⁴, which closes the same.

Extending laterally from near the top of 55 the fire-box of the furnace to the side walls are the flues *C*, which communicate at their

outer ends in a longitudinal flue *c*², from which upwardly-extending flues *c* in said side walls lead to the top of said walls and at their upper ends open inwardly of the oven through somewhat restricted openings or passages *c'*. As shown, a bridge-wall *D* and *D'*, respectively, extends transversely at the front and the rear ends of the oven parallel with and adjacent the end walls thereof, providing a down-flue 65 between the same and said end walls. Said bridge-walls extend upwardly to a point below the passages *c'*, opening near the top of the oven and indicate the limit to which the oven can conveniently be filled with the casting and 70 cementing material.

Extending longitudinally of the oven are flues *D*² *D*³ and *D'* *D*⁵, of which the flue *D*² is positioned above the flue *D'* and the flue *D*³ above the flue *D*⁵. The flues *D*² and *D*³ extend 75 through the bridge-wall *D'* and the end wall *B*² and communicate with downwardly-extending flues *d*, which open into a longitudinal horizontal flue *d'* beneath the laterally-directed flues *C* and lead to the stack *A'*. Said 80 lower flues *D*⁴ and *D*⁵ communicate with the down-flue between the bridge-wall *D'* and rear end *B*² of the furnace and extend continuously 85 through the bridge-wall *D* and end wall *B*³ and communicate in down-flues *d*² at the end of said oven adjacent the stack and which open into said longitudinal flues *d'*, opening into said stack.

Arranged alternately and extending inwardly from each of the side walls are a plurality of horizontal transverse flues *E* *E'*, each of which extends to a point above the longitudinal flue *D*² or *D*³ adjacent the opposite wall and at their extremities are built upwardly to afford an upwardly-opening end *e*, 90 which extends above the material packed in said oven.

Sliding dampers *d*⁴ and *d*⁵ are provided in each of the flues *D*², *D*³, *D'*, and *D*⁵ at the points where the same communicate with the 100 down flues leading to the stack, thereby enabling the draft through said flues to be perfectly regulated, and view-apertures are provided in the end walls in alinement with said flues at the ends opposite said dampers and 105 also in alinement with transverse flues *E* and *E'*, which are adapted to be closed by means of inserted brick *d*⁶ or other suitable means when the oven has become thoroughly heated and the draft has been properly regulated.

110 The operation is as follows: The castings or other material to be annealed or malleable-

ized are packed loosely in the oven with any suitable cementing material, and as the work of filling the oven progresses the flues D^4 and D^5 and later the flues D^2 and D^3 and the lateral flues E and E' are built in place, supported upon and embedded in the material to be treated, and are constructed of fire-bricks, tile, or any suitable material. The oven may be entirely filled to a height corresponding approximately with that of the end bridge-walls, after which a layer of clay, sand, or any suitable or preferred material may be spread over the mass, and the oven is then closed. The oven is fired from one or both ends in the usual manner. The hot air from the furnace passing inwardly and upwardly through the flues C , enters the flue c^2 , and is distributed equally to the flues c , from which a part enters the top of the oven through the restricted passages c' and is drawn downwardly between the end walls and bridge-walls and flows oppositely through the contents of the oven, through the flues D^2 D^3 D^4 D^5 , and then through the flues d and d^2 to the longitudinal flue d' , leading to the stack A' . Owing to the restriction of the outlet at the upper end of the flues c , a large portion of the heat is directed into the oven through the flues E and E' , which are supported on and bedded in the mass contained in the oven. The heat is thus conveyed to all parts of and through the mass by means of said longitudinal flues D^2 to D^5 , inclusive, and the transverse flues E E' and the upwardly-extended ends e also bedded in said material. It follows that all parts of the mass respective to the size of the oven or the castings is uniformly and much more efficiently heated than has heretofore been possible, enabling the temperature of the material to be treated to be raised to the required point much more quickly and to be maintained more uniformly than heretofore. After the desired temperature has been attained, as can be determined by inspection through the view-apertures, the dampers previously used merely for regulating purposes are closed, as shown in Fig. 3, and the view-apertures sealed up to retain the heat in said oven, and the oven is allowed to stand for the required length of time to complete the process, after which it is opened and cooled and the castings removed.

Obviously by the construction described castings of any desired size may be malleableized as readily as has heretofore been possible with smaller castings, and much greater quantity of castings may be treated in an oven of a given size than would be the case were saggers employed.

Obviously any number or size of transverse or longitudinal flues may be provided through the material, and the same may be arranged at any desired distance apart to divide the interior of the oven into relatively small sections, about which the heat is conducted, and any desired arrangement of flues may be pro-

vided to afford means for conveying heat to all parts of and through the material treated, and many details of construction may be varied without departing from the principles of this invention.

I claim as my invention—

1. An annealing-oven adapted to be filled with a mass of castings to be annealed, conducting-flues extending upwardly through the side walls and opening into the oven near the top thereof and horizontal flues communicating therewith and opening upwardly through the mass of castings.

2. In an annealing and malleableizing oven, horizontal flues passing through the oven above the floor and supported on the material to be treated and open, upwardly-directed ends on some of said flues opening above said material.

3. An annealing-oven comprising side and end walls, heat-flues in the side walls, bridge-walls adjacent the end walls and affording flues between the same and affording an inner bed into which the material to be treated is packed, longitudinal and transverse heat-flues extending therethrough and bedded in said material and adapted to convey heat through all parts of the same and means regulating the draft through said flues.

4. An annealing-oven comprising hollow end and side walls adapted to convey heat therethrough and affording an inner closed chamber, all the walls of which are adapted to be heated and into which the material to be treated is packed, flues communicating with corresponding flues in the side walls and bedded in said material and having upwardly-directed ends extending above the same and longitudinal flues bedded in said material and communicating at one or both ends of the oven with a flue leading to the stack.

5. An annealing-oven comprising hollow walls, means for conveying heat therethrough, flues connected in the end walls and adapted to convey heat through the material to be treated and flues arranged at an angle therewith and projecting into the oven.

6. An annealing-oven adapted to be filled with the material to be treated packed therein without saggers and comprising a source of heat, end and side walls having flues therein communicating with the source of heat and heat-conveying flues supported in and extending through the material when the oven is filled and acting together with the heated end and side walls of the oven to heat said material uniformly, and flues beneath the floor of the oven, communicating with the aforesaid flues and leading to the stack.

7. An annealing-oven comprising a source of heat, hollow end and side walls adapted to convey heat therethrough, flues communicating in said hollow walls and projecting into the oven and dividing the interior of the oven into relatively small sections into which and

around the flues material to be treated is packed without saggers and means for regulating the draft through said flues.

8. An annealing-oven comprising a longitudinal fire-box, side and end walls above said box, flues leading from said fire-box upwardly to the side walls and provided with restricted openings adjacent the top of the oven, transverse flues leading therefrom below said openings, upwardly-directed inner ends thereon, longitudinal flues below said transverse flues and brick walls adjacent said end walls.

9. An annealing-oven comprising bottom, side and end walls adapted to convey heat therethrough, a plurality of longitudinal flues opening into said end walls, transverse flues above the same extending from one side wall into close proximity with the opposite side wall, means for applying heat to said oven and means for regulating the draft through said flues.

10. An annealing-furnace provided with an oven, a plurality of vertical flues at each end of the oven and removable flues disposed horizontally across the oven, embedded in the material to be treated and communicating at each end with the vertical flues at the ends of the oven.

11. A malleableizing and annealing oven comprising a source of heat, an inclosed oven adapted to receive the material to be treated packed therein, flues in the walls of said oven extending partly around the same both laterally and longitudinally and centrally-disposed longitudinal flues extending through the material to be treated.

12. A malleableizing and annealing oven comprising a source of heat, an inclosed oven adapted to receive the material to be treated packed therein, flues extending partly around said oven both laterally and longitudinally and centrally-disposed longitudinal flues extending through the material to be treated, a

stack into which said flues open and dampers adapted to regulate the draft in each of the 45 flues opening to the stack.

13. In a malleableizing and annealing oven in which the castings to be treated are packed without pots, a flue built therein and supported upon and passing through the material 50 to be treated, a stack with which said flue communicates and a damper adapted to control the draft through said flue.

14. In a metal-treating oven into which the articles to be treated are packed together with 55 packing material and without saggers, a plurality of flues built therein and supported upon and passing through the material to be treated, a stack with which said flues communicate, means for inspecting the oven and flues and 60 a damper for each flue acting to regulate the draft therethrough.

15. A malleableizing and annealing furnace having an open floor adapted to receive loosely, the castings to be treated together with 65 cementing material, flues adapted to be supported in part upon the material to be treated and extending therethrough and adapted to diffuse heat through the mass to be treated and means regulating the draft to said flues. 70

16. In a device of the class described the combination with an oven adapted to receive castings therein, of longitudinal flues in said oven, part of which are built up on said castings, transverse flues beneath the oven, upwardly-opening flues in the side wall, a stack 75 and flues leading from said longitudinal flues to said stack.

In testimony whereof I have hereunto subscribed my name in the presence of two sub- 80 scribing witnesses.

WILLIAM L. CASADAY.
